UNITED STATES PATENT OFFICE.

WILLIAM A. MACK, OF NORWALK, OHIO, ASSIGNOR TO THE STANDARD SEWING MACHINE COMPANY, OF CLEVELAND, OHIO, A CORPORATION OF OHIO.

SHUTTLE-RACEWAY SUPPORT FOR SEWING-MACHINES.

SPECIFICATION forming part of Letters Patent No. 778,202, dated December 20, 1904.

Original application filed April 25, 1885, Serial No. 163,895. Divided and this application filed September 19, 1892. Serial No. 446,268.

To all whom it may concern:

Be it known that I, WILLIAM A. MACK, a citizen of the United States, and a resident of Norwalk, in the county of Huron and State of Ohio, 5 have invented new and useful Improvements in Sewing-Machines, of which the following is a specification.

The invention forming the subject-matter of the present application, which is a division 10 of a prior application on which has been issued Letters Patent No. 519,539, dated May 8, 1894, relates to improvements in sewing-machines, and particularly to that class of sewing-machines employing a rotary or oscillating shuttle 15 supported to operate in a raceway. In this class of machines the shuttle-supporting raceway is usually located in some part having a fixed relation to the bed-plate and to the path of movement of the needle. As the shuttle 20 supported in such raceway is therefore non-adjustable with respect to the path of movement of the needle, it is the usual practice in adjusting the parts for the purpose of having the needle move in proper relation to the 25 shuttle during the stitch-forming operation to either shift the overhanging arm, with the needle-bar and other supported parts on the bed-plate, or else bend the needle or needle-bar. As both of these methods are obviously undesirable, however, it has been the main object 30 of my present invention to provide a sewing-machine having an improved means for permitting of any necessary adjustment of the parts in securing the proper coöperation of the needle and the shuttle in the stitch-forming operation.

In carrying the invention into effect I locate the shuttle-raceway in a suitable frame and adjustably support said frame within a 40 seat formed to receive the same at the under side of the bed-plate of the machine, the arrangement of the parts being such that the raceway-frame may be adjusted within its said seat in a direction to move the supported 45 shuttle either toward or from the path of movement of the needle, and thereby permit the desired positioning of such parts relatively to each other.

Referring to the accompanying drawings, forming part of this specification, Figure 1 is 50 a front end elevation, with the bed-plate in section, of a part of a "Standard" rotary-shuttle sewing-machine embodying my invention. Fig. 2 is a front elevation of the shuttle-raceway frame with its contained 55 shuttle detached from the machine, and Fig. 3 is a sectional elevation on line 33 of Fig. 1.

The sewing-machine shown in the drawings with my invention applied thereto comprises the bed-plate *a*, the needle-plate *a'*, the vertically-reciprocating needle *a''*, the rotary shuttle *b*, and the bobbin-case *d*, the said needle and the shuttle being adapted to coöperate in the formation of a stitch in the usual manner. In the present case the circular raceway in which the 65 shuttle is supported and operates is located in a frame, (designated generally by *f*), which comprises a body-ring *f'* and a detachable cap-ring *f''*, the said body-ring being provided on its inner peripheral wall and at the front edge thereof with the circular raceway *f''*, in which the shuttle is supported at its peripheral or race-bearing edge, and the cap-ring *f''* being detachably secured to the said body-ring by suitable fastening means, such as the screws 75 *f''*, with its inner edge overlapping the adjacent edge of the shuttle and serving to removably retain the latter in its said raceway.

The raceway-frame *f* is adapted to be supported at the under side of the bed-plate *a* in 80 such position as to assure the proper coöperation of the contained shuttle *b* with the needle *a''* during the stitch-forming operation, and the means for so supporting the said raceway-frame, as herein shown, comprises a 85 hanger *h* on the under side of the bed-plate having an opening extending therethrough in a direction at substantially right angles to the path of movement of the needle, which forms a seat within which the frame *f* is removably 90 and adjustably secured by suitable fastening means, such as the screws *h'*. With the raceway-frame *f* thus supported it may be readily shifted back and forth within its seat to properly adjust the position of the contained 95 shuttle relatively to the path of movement of

the needle and also by reason of its circular form be turned within its seat to properly adjust the position of its needle-opening f^4 relatively to the path of movement of the needle.

5 A further and important feature of the shuttle-raceway being located in a relatively small frame that is detachable from the machine is the fact that it enables such frame to be constructed and provided with the shuttle and 10 other associated parts without the necessity of handling the heavy and cumbersome bed-plate casting for such purpose as would be required if the shuttle-raceway were formed in said bed-plate itself.

15 What I claim is—

1. In a sewing - machine of the class described, the combination of a bed-plate provided with a seat below its upper surface, a raceway - frame adjustably supported within 20 said seat and being provided with a circular raceway, and means for securing said frame in a stationary adjusted position, for the purpose set forth.

2. In a sewing - machine of the class described, the combination of a bed-plate provided with a seat below its upper surface, a circular raceway-frame adjustably supported within 25 said seat and being provided with a

circular raceway, and means for securing said frame in a stationary adjusted position, for 30 the purpose set forth.

3. In a sewing - machine of the class described, the combination of a bed-plate provided with a stationary support or hanger on its under side having a seat or opening extending therethrough in a direction at right angles to the path of movement of the needle, a shuttle-raceway frame adjustably supported within said hanger and being provided with a circular raceway, and means for securing 40 said frame in a stationary adjusted position relative to the path of movement of the needle, for the purpose set forth.

4. In a sewing - machine of the class described, the combination of a bed-plate provided with a hanger on its under side having a circular seat therein, a circular shuttle-raceway frame removably supported within said seat and being provided with a circular raceway, and means for securing the frame in a 45 stationary position in its said seat.

WILLIAM A. MACK.
